(57) **CLAIM**

I claim the ornamental design for an imaging device, as shown and described.

DESCRIPTION

FIG. 1 is a perspective view of an imaging device;
 FIG. 2 is a front elevation view thereof;
 FIG. 3 is a right side elevation view thereof; and,
 FIG. 4 is a left side elevation view thereof.
 The appearance of any undisclosed portions of the present invention is not claimed.
 Broken lines and unshaded portions contained within broken lines are not claimed.

1 Claim, 4 Drawing Sheets(56)
